UNITED STATES PATENT OFFICE.

RICHARD J. McCARTY, JR., OF ALBANY, NEW YORK, ASSIGNOR, BY MESNE ASSIGNMENTS, TO BETHLEHEM STEEL COMPANY, A CORPORATION OF PENNSYLVANIA.

MEANS FOR CONTROLLING THE OPERATION OF BOOSTER MOTORS OR AUXILIARY PROPULSION UNITS.

Application filed February 21, 1924. Serial No. 694,187.

This invention relates to an improved means for controlling the operation of booster motors or auxiliary propulsion units and is primarily designed for the purpose of automatically governing the supply of steam or other energizing medium to the booster motor cylinders and effecting a proper entrainment of the driving shaft of the motor with the axle to be driven thereby.

10 In an application filed by John A. McGrew and James T. Loree on December 15th, 1921, Serial No. 522,525, there is described and claimed such an automatic control means for vehicle propulsion units or locomotive boosters wherein a pressure actuated piston valve is directly interposed in the steam supply line leading to the booster cylinders, said valve piston being operatively connected to a movable entraining gear whereby, under the initial pressure influence of the steam, said valve piston is moved to effect an initial slow speed operation of the booster motor so that the entraining gear is positively rotated by the driving shaft at approximately the speed of rotation of the gear on the truck axle as the entraining gear is moved into enmeshed relation with the gear on said axle. When full entrainment of the gears takes place, said valve piston is in such a position as to permit of the free passage of steam in maximum volume to the booster cylinders so that the booster is operated at high speed. This specific single automatic valve control for the booster motor is also fully described and specifically claimed in Patent No. 1,447,352, granted to the said John A. McGrew and James T. Loree on March 6th, 1923.

It is the primary object and purpose of the present invention to provide another automatic control means for such booster motors whereby the same initial idling operation of the booster during the entraining action may be secured, the said means being also actuated solely by the pressure influence of the steam supplied to the booster motor cylinders. In the present instance, however, I provide separate means for operating the entraining gear and for controlling the supply of motive fluid to the booster cylinders in lieu of the single automatic control valve as shown in said patent above referred to. Further, in the present instance, the cylinder with the piston operating therein connected to the entraining gear is not located directly in the steam supply line but is spaced therefrom and has a branch pipe connection with the steam supply pipe. Therefore, it will be appreciated that it is not necessary to locate the booster steam supply pipe contiguous to the entraining gear, but said pipe might be arranged in any other convenient location so that there will be ample clearance space above the ties or the other parts of the road bed.

It is another object of the present invention to provide a very simple means whereby the quantity of steam initially admitted to the booster motors may be varied and the idling speed of the booster regulated accordingly.

With the above and other objects in view, the invention consists in the improved control means for booster motors and in the form, construction and relative arrangement of the several parts thereof as will be hereinafter more fully described, illustrated in the accompanying drawings, and subsequently incorporated in the subjoined claims.

In the drawing wherein I have illustrated more or less diagrammatically, one practical embodiment of the present improvements and in which similar reference characters designate corresponding parts throughout the several views:

Figure 1 is a longitudinal sectional view illustrating the several elements of the automatic control means in their normal relative positions and with the booster disentrained from the axle it is to drive; and

Figure 2 is a similar view showing the parts of the control means after they have operated to first entrain the booster driving shaft with the truck axle and then supply steam in maximum volume to the booster motor cylinders.

The automatic motor control mechanism which I shall presently describe in detail, was primarily designed for the purpose of automatically effecting an operative connection or entrainment of a booster motor driving shaft with one of the truck axles constituting a load bearing or sustaining axle for the tender of a locomotive. However, in so far as my present improvements are concerned, the booster motor may be used for positively driving one of the axles of the pilot or trailer truck of the locomotive or

the truck axle of any one of the train carriages, the purpose being to provide means for increasing tractive power and aiding the main engine of the locomotive in the propulsion of the train at low speeds, as in starting from a terminal or upon controlling grades.

In the accompanying drawing I have illustrated only so much of the booster motor and the truck with which it is associated, as will enable the nature of my improvements to be clearly understood. Accordingly, I have shown merely the spaced truck axles 5 and 6 upon the opposite ends of which the weight supporting wheels 7 and 8 respectively, engaged upon the track rails, are secured in any approved manner. The booster motor includes cylinders of suitable dimensions, one of which is indicated at 9, the pistons operating within said cylinders having suitable driving connections (not shown) with a drive shaft 10. Preferably, I mount or arrange this booster or propulsion unit between and upon the spaced axles 5 and 6 in the manner shown in the patent granted to John A. McGrew and James T. Loree on April 11, 1922, No. 1,412,250.

The drive shaft 10 is arranged contiguous to and in parallel relation with the truck axle 6 but normally has no driving connection therewith. For the purpose of entraining said driving shaft with the axle 6 to impart a positive driving impulse to the latter, any suitable type of disengageable gearing might be employed. However, I have herein shown a conventional type of such gearing consisting of a gear element 11 fixed upon the driving shaft 10 and a gear element 12 fixed upon the axle 6. An idler gear 13 is in constant mesh with driving gear 11 and is mounted for planetary movement as well as axial rotation in one fork of an angular rocker member 14 which is mounted for oscillating movement upon the drive shaft 10.

Steam is supplied to the booster motor cylinders through the pipe 15 which is preferably connected to the superheated steam supply pipes exteriorly of the locomotive boiler which supply the main engine cylinders with superheated steam. A cylinder 16 is suitably mounted and arranged in spaced relation to the steam supply pipe 15 and at one of its ends is connected to said supply pipe by means of the branch pipe 17. A piston 18 reciprocates in this cylinder and has a rod 19 operatively connected to the other arm of the rocker member 14. The piston 18 is urged in one direction in said cylinder to its normal position by means of a suitable spring 20.

The steam supply pipe 15 is connected to one side of a second cylinder 21 intermediate the ends thereof, said cylinder being located between the cylinder 16 and the motor

cylinders 9. Said cylinders are connected to the cylinder 21 through the medium of the pipe 22, the point of connection of said pipe to the cylinder 21 being longitudinally spaced from the point of connection of the supply pipe 15 to said cylinder. The pipe 22 is also connected with the cylinder 21 by means of a by-pass connection 23, in which there is preferably arranged a removable orificed plug 24. The diameter of the orifice determines the volume of steam passing from the cylinder 21 through the by-pass connection and hence through pipe 22 to the booster cylinders. It will, however, be understood that by providing interchangeable plugs having orifices of different diameters, an initial idling operation of the motor at various speeds may be obtained.

In the cylinder 21 a balanced piston having spaced heads 25 and 26 respectively, is arranged, said heads being connected by the rod or stem 27 which extends through one end of the cylinder 21 and is operatively connected to one end of a lever 28 which is fulcrumed intermediate of its ends as at 29 upon a suitable supporting bracket. The other end of this lever is operatively connected to the end of rod 19 of the piston 18 which operates in the cylinder 16, the arm of rocker member 14 being connected to said rod at a point intermediate of its ends, as clearly shown in the drawing. A coil spring 29 surrounds the lower end of the rod 27 below the piston head 25 and bears against the lower end wall of the cylinder 21. This spring, however, is not essential and may be dispensed with, if desired.

I also preferably provide a circulation by-pass connection 30 between the lower end of cylinder 16 and said supply pipe 15 at a point intermediate the branch connection 17 and the cylinder 21. This by-pass 30 insures the continuous circulation of live steam through the cylinder 16 so that a steady and continuous pressure will be exerted against the piston 18.

In the operation of the device above described, assuming that the parts are in the normal position shown in Figure 1 of the drawing, when the main throttle valve is opened to supply steam to the main engine cylinders, steam also passes through pipe 15 and into the upper end portion of the cylinder 21, from which it passes in small volume through the orificed plug 24 and by-pass 23 to the pipe 22 and thence to the motor cylinders. By thus initially admitting a small quantity of steam to the cylinders 9, the booster motor is idly operated at low speed, thus imparting slow rotation to the driving shaft 10 and gear 11 thereon whereby the power transmitting gear 13 is also rotated upon its axis, at approximately the speed of rotation of the fixed gear 12 on the axle 6. The cumulative pressure influence of the

steam which builds up in the upper portion of cylinder 21, pipe 15 and the branch connection 17 to the cylinder 16, during this idling operation of the motor acts against the piston 18 in said cylinder 16, moving the same against the pressure of spring 20 whereby the member 14 is rocked to impart a planetary movement to the idler gear 13, while it is being rotated upon its axis, and thus effecting a proper and full meshing engagement of this rotating idler gear with the rotating gear 12 on the axle 6 so that the gear 13 thus becomes a positive power transmitting element imparting a driving impulse to said axle. The cumulative steam pressure thus also operates at the same time through the lever connection 28 with the upper end of the piston rod 27 to force the piston in cylinder 21 downwardly to the position shown in Figure 2 of the drawing, in which the pipes 15 and 22 are placed in direct open communication with each other through said cylinder so that a full or maximum quantity of steam will then be supplied through the pipes 15 and 22 to the motor cylinders 9. Thus, it is apparent that as soon as a full intermeshing engagement or entrainment of the idler gear 13 with the axle gear 12 is obtained, the booster motor will be operated at full power, thereby positively driving axle 6 and producing a tractive effort upon the rails in proportion to the power output of said motor. Such additional tractive effort is a distinct supplement and aid to the main locomotive engine to accelerate movement of the train from terminals or on grades, it being understood that at comparatively low speeds there is a considerable surplus potential steam energy in the locomotive boiler which is not consumed in driving the main engine.

From the foregoing description considered in connection with the accompanying drawing, the construction, manner of operation and several advantages of my present improvements will be clearly and fully understood. It will be seen that I have succeeded in providing means whereby the steam pressure actuated piston for the booster entraining gear may be arranged comparatively remote from the steam supply pipe 15 for the motor cylinders, while at the same time a proper initial idling operation of the motor during the entraining operation with a subsequent full speed operation thereof is secured, whereby the possibility of stripping or mutilating the teeth of the entraining gears is obviated. While I have illustrated and described one adaptation of my invention which I believe to be entirely practical, it is nevertheless to be understood that the device might also be exemplified in other alternative structures and I, therefore, reserve the privilege of resorting to all such legitimate changes in the form, proportion

and relative arrangement of the several parts as may be fairly embodied within the spirit and scope of the invention as claimed.

I claim:

1. In combination with a booster motor, means for entraining said booster motor with said axle including a power transmitting element movable to and from an entrained position, a steam supply pipe for the booster motor cylinders, a cylinder in communication with the supply pipe, a steam pressure actuated piston in said cylinder operatively connected with said power transmitting element, and means arranged between said cylinder and the booster motor cylinders to initially supply steam in small quantity to said cylinders and effect an idling operation of the motor during the entraining action and to thereafter supply steam in greater quantity to the booster cylinders to effect a full power operation of the booster, said means including a movable piston, and an operative connection between said pistons whereby they are simultaneously actuated by the cumulative pressure influence of the steam during the idling operation of the motor.

2. In combination with a booster motor, means for entraining said booster motor with said axle including a power transmitting element movable to and from an entrained position, a steam supply pipe for the booster motor cylinders, a cylinder in communication with the supply pipe, a steam pressure actuated piston in said cylinder operatively connected with said power transmitting element, and means arranged between said cylinder and the booster motor cylinders to initially supply steam in small quantity to said cylinders and effect an idling operation of the motor during the entraining action and to thereafter supply steam in greater quantity to the booster cylinders to effect a full power operation of the booster, said means including a movable piston, an operative connection between said pistons whereby they are simultaneously actuated by the cumulative pressure influence of the steam during the idling operation of the motor, and means whereby the idling speed of the booster motor may be variably regulated.

3. In combination with a booster motor, means for entraining said booster motor with said axle including a power transmitting element movable to and from an entrained position, a steam supply pipe for the booster motor cylinders, a cylinder in communication with the supply pipe, a steam pressure actuated piston in said cylinder operatively connected with said power transmitting element, and means arranged between said cylinder and the booster motor cylinders to initially supply steam in small quantity to said cylinders and effect an

idling operation of the motor during the entraining action and to thereafter supply steam in greater quantity to the booster cylinders to effect a full power operation of the booster, said means including a movable piston, and a lever fulcrumed intermediate of its ends and operatively connected at its

respective ends to said pistons whereby the latter are simultaneously actuated by the cumulative pressure influence of the steam 10 during the idling operation of the motor.

In testimony that I claim the foregoing as my invention, I have signed my name hereto.

RICHARD J. McCARTY, JR.
